[57] CLAIM

The ornamental design for an electrode tip for a plasma arc cutting torch, as shown and described.

DESCRIPTION

FIG. 1 is a front elevational view of an electrode tip for a plasma arc cutting torch showing my new design;

FIG. 2 is a top plan view thereof;

FIG. 3 is a left end elevational view thereof;

FIG. 4 is a right end elevational view thereof;

FIG. 5 is a rear elevational view thereof; and,

FIG. 6 is a bottom plan view thereof.

1 Claim, 1 Drawing Sheet

FIG. 3.

FIG. 1.

FIG. 4.

FIG. 2.

FIG. 5.

FIG. 6.
